US00D948728S

(12) **United States Design Patent** (10) Patent No.: **US D948,728 S**
(45) Date of Patent: **** Apr. 12, 2022**

(54) **SENSOR DEVICE FOR BALANCE REHABILITATION TRAINING APPARATUS**

(71) Applicant: **Neofect Co., Ltd.**, Seongnam-si (KR)

(72) Inventor: **Byeong Geol Park**, Icheon-si (KR)

(73) Assignee: **Neofect Co., Ltd.**, Seongnam-si (KR)

(**) Term: **15 Years**

(21) Appl. No.: **35/510,455**

(22) Filed: **Mar. 13, 2020**

(80) **Hague Agreement Data**

Int. Filing Date: **Mar. 13, 2020**

Int. Reg. No.: **DM/210422**

Int. Reg. Date: **Mar. 13, 2020**

Int. Reg. Pub. Date: **Oct. 2, 2020**

(51) **LOC (13) Cl.** 24-02

(52) **U.S. Cl.**

USPC **D24/187**; D24/186

(58) **Field of Classification Search**

USPC D24/186-189

CPC A61B 2560/0462; A61B 2560/0412

(57) **CLAIM**

The ornamental design for a sensor device for balance rehabilitation training apparatus, as shown and described.

DESCRIPTION

1. Sensor device for balance rehabilitation training apparatus

1.1 : Perspective

1.2 : Front

1.3 : Back

1.4 : Top

1.5 : Bottom

1.6 : Left

1.7 : Right

The broken lines depict portions of the sensor device for balance rehabilitation training apparatus that form no part of the claimed design.
